UNITED STATES PATENT OFFICE.

SAMUEL LAUFF, OF WATERBURY, CONNECTICUT.

QUICK-RELEASE WRENCH.

1,136,539.

Specification of Letters Patent. Patented Apr. 20, 1915.

Application filed February 4, 1914. Serial No. 816,528.

To all whom it may concern:

Be it known that I, SAMUEL LAUFF, a subject of the Emperor of Austria-Hungary, and a resident of Waterbury, in the county 5 of New Haven and State of Connecticut, have invented certain new and useful Improvements in Quick-Release Wrenches, which improvements are fully set forth in the following specification.

10 This invention relates to improvements in devices of that class available for manipulating nuts, suitably-headed bolts, and the like, and each thereof embodying a pair of jaws, one of which is adjustable, slowly 15 through the medium of coacting threads or quickly through the annulment of the coacting relation of said threads, toward and away from the other, such devices being well-designated quick-release wrenches.

20 The object of this invention is to provide a wrench of the character above indicated, which shall be simple and comparatively inexpensive as regards its construction; durable, efficient and reliable in practical service; 25 markedly convenient in its application to practical purposes, and which shall possess certain well-defined advantages over prior analogous devices.

The invention consists in the combinations, details and parts whereby, together with the novel disposition and relative arrangement of said parts, the attainment of the foregoing object is rendered practicable, all of which will be hereinafter more specifically referred to and set forth in the appended claim.

The invention is clearly illustrated in the accompanying drawing, wherein—

Figure 1 is a side elevation of a quick-release wrench embodying my said improvements. Fig. 2 is a plan view, showing the same as it appears when turned obversely on its longitudinal axis ninety degrees from the position it is shown as occupying in Fig. 1. Fig. 3 is an enlarged detail view, the shank, including the fixed jaw ~~co-~~ joined therewith, being shown in side elevation, and the adjustable jaw, including certain parts supported thereby, being mainly shown in central, vertical, longitudinal section, as along the broken line $\alpha-\alpha$, of Fig. 2. Fig. 4 is a view, partly in end

elevation and partly in cross-section, as along the broken line $y-y$ of Fig. 1, of the movable-jaw extension. Fig. 5 is a view 55 showing in perspective and detached, the nut-controlling arbor made use of. Fig. 6 is a view partly in end elevation and partly in cross-section, as along the broken line $z-z$ of Fig. 2, of the arbor-controlling 60 keeper made use of. Fig. 7 is a perspective view of said keeper, detached.

Having reference to the accompanying drawing, wherein similar reference-numerals denote like parts throughout the respective views, I make use in carrying out my invention, of a stock or shank 2, fitted at one end thereof with a handle 2', at its opposite end with a fixed jaw 2'', and provided along its lower edge with segmental threads 3; 70 also a jaw extension 3', fitted with a jaw 3'', strapped to the shank 2, for movement to and fro therealong and as through the medium of upstanding yoke 4, 4', whereby the jaw 3'' becomes adjustable relatively to 75 ward and away from the jaw 2'', and cut away from its under side upwardly, as at 4'', for the accommodation of a circumferentially threaded nut 5, the threads of the latter normally engaging the segmental 80 threads 3, and whereby the adjustability of the jaw 3'' relatively to the jaw 2'' may be effected and controlled, all as in common practice.

In practice it frequently becomes desirable that the extension 3', with the jaw 3'' carried thereby, may be oppositely adjusted between more or less distantly separated points along the shank 2, and independently of the threads, respectively, aforesaid; 90 and as a condition precedent to this end is the disengagement of the circumferential threads afforded by the adjusting-nut 5 from the segmental threads 3, or vice versa, I loosely mount said adjusting-nut on a rotatable arbor 5', which bears at its inner end in a socket 5'', formed in the extension 3', at the inner side of the nut 5, and in a bushing 5''', at the opposite side of said nut, said bushing being pinned or otherwise 95 fastened within an opening 6, formed in the extension 3' at the rear end-portion thereof, and in axial alignment with the socket 5''. Arbor 5' has a medial portion 6'', en-

larged diametrically and offset eccentrically to the axis thereof, said medial portion being loosely occupied by the adjusting-nut 5. Hence, it will be observed that upon the 5 arbor 5' being caused to undergo, say, a half-revolution in one direction, as to the position indicated in full lines in Fig. 3, the adjusting-nut 5 will be caused to move bodily away from the shank 2 a distance 10 sufficient to disengage the threads afforded by said adjusting-nut from the segmental threads 3, thereby liberating the extension 3', with its jaw 3'', for free movement to and fro along the shank aforesaid; while 15 upon said arbor being caused to undergo, in either direction, say, an additional half-revolution, as to the position indicated in broken lines in Fig. 1, the adjusting-nut aforesaid will be caused to move bodily 20 in the direction of the shank 2 a distance sufficient to disengage the threads afforded circumferential threads afforded by said adjusting-nut with the segmental threads aforesaid, under which condition of the 25 parts, the extension 3', with the jaw carried thereby, may only be moved to and fro along the shank 2 by duly turning the adjusting-nut 5, as will be readily understood.

It is desirable that means be provided 30 whereby may be facilitated the manipulation of the arbor 5', for causing the adjusting-nut 5 to move toward and recede from the shank 2, as stated, and for adequately locking said arbor against casual rotation 35 when so oppositely adjusted; and in this connection I provide a keeper 6'', which is mounted on the arbor aforesaid, at the outwardly extended portion thereof, and in a manner to be movable both rotarily therewith and longitudinally therealong. As 40 here shown, the keeper 6'', which may be cylindrical or otherwise in cross-section, is provided with a longitudinal bore 7, to facilitate its mounting on the arbor 5', substantially as indicated in the drawing, said arbor being provided with a suitable, longitudinal, slot-like recess 7', into which freely projects the inner end of a key or pin 7'' inserted, by way of a suitable opening provided therefor, radially through the body of said keeper, all as clearly shown in Fig. 6, and whereby said keeper is attached to said arbor in a manner to be movable therewith and longitudinally therealong.

55 The arbor 5' is provided at its outer end with a terminal disk 8, between which and a shoulder 8' there is interposed a spiral spring 8'', which spring tends at all times to elastically urge the keeper aforesaid in 60 the direction of, and against, the rear end of the extension 3'; and the bore 7, from a suitable point interiorly thereof, to its rear terminus, being enlarged diametrically, both for the formation of the shoulder 8' and the 65 accommodation of the spring 8''.

The disk 8, which approximately coincides diametrically with the diameter of the enlarged portion of the bore 7, is disposed on the arbor 5', at its rearwardly projecting portion, so as to be surrounded peripherally 70 and housed at all times by the keeper 6'', said disk serving, incidentally and accordingly, as an auxiliary bearing for said keeper, whereby the latter is caused to act more steadily with, and in its movements 75 longitudinally along, the arbor aforesaid.

The keeper 6'' is provided at its front end with a tongue or detent 9, preferably oppositely tapered as shown, and which normally, under the controlling action of the 80 spring 8'' on said keeper, seats within a suitable recess 9', formed in the extension 3', at its rear end, thereby substantially locking the arbor 5' against casual rotation.

As will be noted, it is advisable that an additional recess, 10, corresponding to 9' and formed oppositely thereto in the extension 3', at the rear end of the latter, be provided; and when desired the keeper 6'' 90 may be provided, at its front end, and oppositely to the detent 9, with a like, additional detent 9''. The opening 6 is enlarged diametrically not only to accommodate the bushing 5'', but to permit the arbor 5', with its enlarged medial portion 6', to be 95 inserted endwise therethrough, as in the operation of assembling the parts.

In practice, the user, grasping the keeper 6'', whose circumferential surface is preferably milled or otherwise roughened, withdraws the same along the arbor 5', against the tendency of the spring 8'', and as to the position indicated in Fig. 3; whereupon, through the medium of said keeper, the arbor 5' may be suitably turned on its axis 100 to cause the adjusting-nut 5 to recede from, or move in the direction of, the shank 2, and for the purposes hereinbefore explained.

It will be seen that my improved quick-release wrench is well adapted for the purposes for which it is intended, and further that the same may be modified to a considerable extent, particularly as regards the means made use of for controlling and manipulating the arbor 5', and also various 115 minor details of the general construction, without departing from the spirit and principle of my invention, as expressed and coming within the scope of the claim hereto appended.

120 I claim:

A wrench comprising a movable-jaw; an adjusting-nut arbor mounted for rotative movement only therein and projecting somewhat rearwardly therefrom; a hollow keeper mounted on the rearwardly projecting portion of said arbor for movement both rotarily therewith and longitudinally therealong; a terminal disk so fixed on the rearwardly projecting portion of said arbor as 130

to be surrounded peripherally and housed at all times by, and to serve incidentally as an auxiliary bearing for, said keeper; and an elastic element, said element being housed at 5 all times by the keeper aforesigned, and tending to elastically urge the same forwardly with respect to said disk, said keeper

being adapted to lockingly engage the jaw-extension aforesigned, at a point in its rotative movement relative thereto.

SAMUEL LAUFF.
